UNITED STATES PATENT OFFICE.

LEWIS B. DAVIS, OF INDIANAPOLIS, INDIANA.

DESIGN FOR A COFFIN-EMBLEM.

SPECIFICATION forming part of Design No. 13,107, dated August 1, 1882.

Application filed May 9, 1882. Term of patent 7 years.

To all whom it may concern:

Be it known that I, LEWIS B. DAVIS, of the city of Indianapolis, in the county of Marion and State of Indiana, have originated and de-5 signed a Coffin-Emblem; and I do hereby declare that the following is a full, clear, and exact description thereof, reference being had to the accompanying drawings, which form a part of this specification.

10 My said invention relates to that class of metal ornaments for coffins or caskets which are commonly affixed to the lid or cover, and are known to the trade as "coffin-emblems."

It consists of the design of a bouquet, includ-
15 ing moss-roses, buds, daisies, ferns, or other appropriate flowers or plants, surrounded by a scroll having the motto "Not lost, but gone before," or a similarly appropriate motto, inscribed thereon.

20 In the accompanying drawings, which are made a part hereof, Figure 1 is a perspective view of a coffin having my newly-designed emblem attached thereto; and Fig. 2 is a plan view, on an enlarged scale, of the said emblem.

25 The design should embody substantially the features shown in the drawings, and the arrangement should be substantially the same,

such variations only being contemplated as shall have the general features shown and described.

The material of which this emblem is usually constructed is the same employed in coffin-hardware generally, which is commonly either silver or other metal silver-plated.

What I claim as new, and desire to secure 35
by Letters Patent, is—

1. The design for coffin-emblems, of a bou-quet of flowers, ferns, or plants in the general form shown, and surrounded by a scroll having a motto thereon, substantially as shown 40
and specified.

2. The design for coffin-emblems, of a bou-quet of flowers, ferns, or plants surrounded by a scroll having the motto "Not lost, but gone before" inscribed thereon, substantially as 45 shown and specified.

In testimony that I claim the foregoing as my own I have hereto affixed my signature in presence of two witnesses.

LEWIS B. DAVIS.
